ATTORNEY

UNITED STATES PATENT OFFICE

JOSEPH H. DWORK, OF NEWARK, NEW JERSEY

MOP WRINGER

Application filed January 17, 1929. Serial No. 333,183.

My invention relates to mop wringers, and it consists in the constructions, arrangement and combination of parts herein described and claimed.

5 An object of my invention is the provision of a mop wringer incorporated as an integral part of the water-pail, and whereby a part of the wringer constitutes the bail of the vessel.

A further object of the invention is to 10 provide a base for the pail which also acts as a pivot upon which the foot treadle is mounted.

A still further object of the invention is to provide a mop wringer in which the 15 wringer rollers are brought into cooperative relation by simple levers and foot treadle.

Additional objects, advantages and features of invention will be apparent from the following description and drawings forming 20 part of this application, wherein,

Figure 1 is a perspective view of my invention when in use for carrying the pail,

Figure 2 is a vertical section showing the parts in wringing position,

25 Figure 3 is a bottom plan view.

In carrying out my invention I provide a receptacle 1 which may be of any well known construction, but having the bottom 2 disposed a distance from the supporting edge 3, 30 thereby providing a recess 4. The edge 3 is provided with notches 5 upon opposite sides, for a purpose which will now be explained. The receptacle is preferably formed from sheet metal.

35 In order to provide ample support for the receptacle 1, I provide a projecting support 6. The projecting support 6 is formed from a single strand of heavy gauge wire, the wire being bent intermediate its ends to provide a 40 treadle pivot 7, having integral portions 8 extended into contact with the outer surface of the edge 3. Each end of the wire is next bent to form foot portions 9, the terminal portions of the wire being bent into circular 45 formation and positioned within the recess 4 by virtue of its entrance through the notches 5. The projecting support 6 may be secured in its position upon the receptacle in any approved manner, as by welding or soldering.

50 Upon one side of the upper edge 10 of the

receptacle, I provide an outwardly pressed trough 11, having side walls 12 and journaled within the trough 11 there is revolvably mounted a roller 13.

Ears 14 are mounted upon the upper edge 55 of the receptacle 1, the bearing of these ears being in a plane parallel to the longitudinal axis of the roller 13.

A handle 15 is provided, and is formed from a single strand of wire, the wire being bent intermediate its length to provide a bight for retaining a roller 16. The extending portions 17 of the wire are bent to form eyelets 18, the extremities of the wire being engaged within the ears 14, as clearly shown 60 in Fig. 1. The portions 17 of the wire are of a length to permit mutual contact between the rollers 13 and 16, when the handle is swung into wringing position.

A foot treadle 19 is associated with the 70 handle 15 for exerting pressure between the rollers 13 and 16. The frame of the treadle 19 is substantially U-shaped in plan, having a bight portion 20 and diverging arms 21 adapted to engage within the eyelets 18. 75 One end of a foot-board 22 is pivotally secured upon the bight 20, while the opposite end is bent to provide a hook 23 for engagement about the pivot 7, when in operative position.

When it is desired to employ the handle 80 15 for transporting the pail, the toe of an operator is positioned beneath the foot-board 22 and exerting an upward push upon the board, such movement imparting an upward swinging movement of the handle 15, so as to assume an upright position.

It should be noted that the projecting support 85 6 herein described provides a bracing means closely adjacent a point where the greatest liability of tipping of the receptacle occurs, and it will therefore be seen that upsetting or tipping of the pail, during wringing operation is eliminated.

In the operation of my device, the handle 90 15 is in its raised position as illustrated in Fig. 1. The mop is positioned upon the roller 13 with the mop strands disposed within the receptacle 1. The operator now places one foot upon one of the rests 9, and 95 100

with his other foot he depresses the foot-board 22. Such downward movement of the foot-board pulls upon the arms 21 which in turn swings the handle 15 toward the trough 11. Continued movement of the treadle will confine the mop between the rollers 13 and 16, and it will be apparent that the degree of pressure upon the treadle determines the amount of squeezing action established between the rollers. Pressure being retained upon the rollers, the handle of the mop is drawn outwardly, causing the strands of the mop to be compressed between the rollers, thereby expelling the water therefrom.

15 Release of pressure upon the foot-board 22 permits the handle 15 to be again swung into upright position, so that the receptacle 1 may be moved from place to place, as the occasion arises.

20 I claim:—

1. A mop wringer comprising a receptacle, oppositely disposed ears secured upon the upper edge thereof, a bail pivoted in said ears and being bent to provide laterally projecting eyelets, a roller carried upon said bail intermediate said eyelets, said receptacle having a trough arranged in a plane parallel to said roller, a roller journaled in said 25 trough, a projecting support for said receptacle, a treadle pivotally mounted thereon, having diverging arms pivoted in said eyelets, whereby upon operation of said treadle in one direction the first named roller will 30 be swung into operative relation with said first named roller.

2. A mop wringer, comprising a receptacle having a circular base, a single strand of wire having its terminal portions bent 40 into circular formation and secured to the base of said receptacle, a treadle mounted upon said wire intermediate said ends, a roller mounted adjacent one side of said receptacle, a swingable bail carried upon the 45 upper edge of said receptacle and having oppositely disposed eyelets, a roller mounted upon said bail and arranged between said eyelets, and a U-shaped frame member pivoted upon said treadle and having diverging 50 arms for engagement in said eyelets, whereby upon movement of said treadle in one direction said rollers will be brought into co-operating relation.

3. A mop wringer, comprising a receptacle, a projecting support mounted at the base of said receptacle, comprising a single strand of wire having an elongated rectilinear portion, mop wringer means mounted on said receptacle and a treadle for actuating 55 said mop wringing means mounted on said rectilinear portion, said rectilinear portion extending coincidently with the axis of rotation of said treadle.

4. A receptacle having a base, apertures 60 in the base, and laterally extending foot

members formed of an elongated member, the ends of said elongated member extending through said apertures and engaging the walls of the base member.

5. A receptacle having a base, apertures 70 in the base, and laterally extending interconnecting foot members adjacent said base formed of an elongated member, the ends of which elongated member pass through said apertures and engage the walls of said base 75 member.

Signed at Washington, in the District of Columbia, this 16th day of January, A. D. 1929.
